UNITED STATES PATENT OFFICE.

TOLLEF O. BAKKEN, OF BODE, IOWA.

OIL CAN.

Application filed September 19, 1921. Serial No. 591,796.

To all whom it may concern:

Be it known that TOLLEF O. BAKKEN, citizen of the United States, residing at Bode, in the county of Humboldt and State of 5 Iowa, has invented certain new and useful Improvements in Oil Cans, of which the following is a specification.

This invention relates to certain new and useful improvements in an oil can of the 10 type embodying a resilient bottom or base for being pressed inwardly to expel the oil from the spout of the can.

The invention has for an object to provide a can or oil container which will expel the 15 lubricant with greater pressure and either drop by drop, under slight pressure, or in a stream under full pressure.

The invention further resides in the provision of a cup-shape member carried on 20 the inside of the resilient bottom to serve in the capacity of a plunger for efficiently expelling the lubricant.

In the drawing,

Figure 1, is a vertical section through an 25 oil container constructed in accordance with the present invention; and

Figure 2, is a horizontal section on line 2—2 of Figure 1.

The oil can in the present instance is substantially hemi-spherical in shape having a 30 resilient bottom 2 and an open top 3 to which is applied the dispensing nozzle or spout 4. The peripheral edge of the bottom is provided with a down-turned flange 5 and is engaged on an annular shoulder or seat 6 about the lower opened end or bottom edge of the can body 1, said edge being extended from said shoulder about the flange 5 and is then bent inwardly and upwardly about 35 40 the same, as indicated at 7, to provide a tight joint between the bottom 2 and the body 1.

The bottom 2 is provided with a central, spheroidal depression 8 which is joined to 45 the surrounding portion thereof by an annular bead 9, the latter increasing the resiliency of the bulged portion 8. A cup-shape expeller member 10 is arranged within the body 1 and is secured at a central point 50 to the bulged portion 8 of the bottom as by a fastener 11, the bottom of said cup-shaped member being also rounded so as to snugly or conformably nest into the bottom. The cup member 10 is also provided with an up-standing, annular flange 12 which collects or 55

confines a certain amount of the lubricant and throws it upwardly or toward the spout when the bottom is pressed inwardly.

In practice, when the outwardly convex bottom portion 8 is pressed inwardly the 60 edge portions of the cup-member 10 are moved inwardly relative to the underlying bead 9, and when the bottom is pressed in to its fullest extent, said bulged portion will then be convexed on its inner side and support the convex bottom of the cup member only at the centrally located point of secure- 65 ment 11. Thus, the inward springing action of the bottom 8 will effect an inward bodily movement of the cup member and since the 70 said resilient portion 8 will spring inwardly with a snap action after having been moved beyond dead center, a like snap action will be imparted to the oil confining cup 10. This will result in a forceful ejection of the 75 lubricant from the spout 4. The heavy pressure obtainable will be accentuated when it is noted that the cup member approaches the side walls of the body 1 and thereby restricts the oil against escaping around the 80 cup member. Thus, the cup member will act as a plunger, being reciprocated within the lower portion of the body by mere flexure of the bottom 8. Consequently, the slight depression or springing of the bottom 85 is materially accentuated by the bodily reciprocation of the broad cup member. The periphery of the cup member, as it approaches the walls of the body, will gradually increase its expelling force by reason 90 of the decrease in the amount of lubricant escaping about the cup member.

A light pressure on the bottom, insufficient to move the bulged portion inwardly beyond dead center, will provide a drop-by-drop or 95 slow expulsion of the oil. An increased flow will follow the application of a heavier pressure. The cup member functions in the capacity of a plunger and moves bodily inwardly with the gradual flexing at the bottom of the oil can. As above stated a small quantity of lubricant will flow under the control of a light pressure on the bottom while a large quantity of the lubricant will be obtainable upon pressing the bottom in- 100 wardly beyond dead center whereupon the latter portion of the inward feed move- 105 ment will occur automatically or after the manner of a snap action. Thus, the final portion of the feed movement will cause the 110

cup plunger to expel a large quantity of lubricant ahead of it. When pressure is released the bottom will return to normal and draw the cup downwardly into nesting relation therewith, which will force any lubricant which may have escaped over the side of the cup outwardly and back over the edge of the cup for being subsequently expelled.

5 What is claimed is:

- 10 10. An oil can comprising a body of substantially semi-spheroidal shape having a bottom centrally and normally depressed for being

sprung inwardly to expel the lubricant, and a cup-shaped member having a depressed bottom for normally nesting in the depressed bottom of the body and secured thereto at a single point whereby the first bottom may be flexed inwardly uninterrupted by reason of the attachment of the cup-shaped member and independently of 15 any flexing of the second bottom.

20 In testimony whereof I affix my signature.

TOLLEF O. BAKKEN.
